UNITED STATES PATENT OFFICE

2,608,354

MECHANISM FOR WINDING TEXTILE THREADS OR FILAMENTS ONTO FLANGED BOBBINS

Harold Whittaker, Chadderton, Oldham, England

Application April 4, 1950, Serial No. 153,815
In Great Britain December 16, 1948

2 Claims. (Cl. 242—43)

1

This invention of improvements in traversing mechanism for winding machines for winding textile threads and filaments relates to such traversing mechanisms in which the thread guide is traversed to and fro through the medium of a grooved cam and more particularly to traverse mechanisms for winding textile threads or filaments on to flanged bobbins.

A disadvantage experienced in winding on such bobbins is that, when a fixed traverse is used, if the bobbins are not accurately positioned relatively to the cam there is a risk that if the throw of the cam carries the thread slightly past the end of the barrel of the bobbin the thread will build up on the package in a slight upward curve against the inner wall of the flange.

Further, when a fixed traverse is used, even when the bobbins are accurately positioned relatively to the cam, it is found that the thread tends to build up in a slight upward curve against the inner wall of each flange, due to a slight dwell of the thread during reversal of the traverse. In such packages the parts adjacent the flanges are more tightly wound and hard than the rest of the package; these hard portions lead to thread breakages during unwinding and uneven penetration during any subsequent dyeing or other wet finishing process.

Alternatively, if the thread fails to reach the end of the barrel there is a tendency for the package to develop slightly rounded corners instead of the desirable square ends. In such circumstances it is found that the thread tends to slip over the rounded corners, and to become embedded between the package and the bobbin flange, and that these embedded threads tend to break during the subsequent unwinding operation.

The present invention overcomes the aforesaid disadvantages by providing traverse mechanism in which the throw of the cam is regulatable to ensure that the thread is correctly laid on the barrel of the bobbin from flange to flange. This is accomplished by continuously varying the points of reversal of the traverse adjacent the flanges so as to counteract the dwell of the thread at such points, thereby winding the thread at the same density in all parts of the package and achieving the desirable square ends.

Traversing mechanism according to the invention comprises in combination a casing, a shaft journalled on said casing, a toothed driving wheel fast on one projecting end of said shaft, a grooved cam splined on said shaft with freedom for slight sliding movement along the shaft alternately in

2

opposite directions, a spider secured on the cam shaft adjacent to the cam and having oppositely extending arms in the form of stub shafts, bevel gear wheels rotatably mounted on said stub shafts in opposed directions each enmeshed with a fixed bevel wheel rigidly mounted on a flanged bush in said casing, eccentric sheaves respectively encasing the boss of the adjacent bevel gear wheel and each respectively embraced by the head of a connecting rod the opposite end of which is connected to the boss of the traverse cam.

In the operation of the traversing mechanism, the traverse cam is rotated by the cam shaft and carries the threaded guide towards one end of the bobbin, the spider also rotates, causing the rotatable bevel gear wheels enmeshed with the fixed bevel wheel to rotate and by means of the eccentric sheaves to move the connecting rods to transmit a slight endwise sliding movement to the traverse cam and so to increase the traverse of the thread guide to ensure that the thread is correctly laid on the bobbin adjacent to the flange, a slight endwise sliding movement in the opposite direction being imparted to the traverse cam at the opposite end of the throw to ensure that the thread is correctly laid at that end of the bobbin, and the rotation of the bevel gear wheels being timed to synchronise with the traverse of the cam to ensure that the sliding movement of the traverse cam takes place alternately at opposite ends of the stroke of the cam, whereby the thread is correctly laid at each end of the bobbin without risk of the thread piling up or alternatively causing rounded corners to be formed, except in a controlled manner.

Description will now be given of a practical embodiment of traversing mechanism according to the invention, reference being made to the accompanying drawings in which the same reference characters indicate corresponding parts in the several figures of the drawings.

Referring to Figs. 1 and 2, the mechanism includes a casing 10 in which is journalled a shaft 11 on one projecting end of which is secured a toothed driving wheel 12. Splined on the shaft 11 is a grooved cam 13 adapted to have a slight sliding movement along the shaft 11 alternately in opposite directions.

Secured on the cam shaft 11 adjacent to the cam 13 is a spider 14 having oppositely extending arms in the form of stub shafts 15. Rotatably mounted on the stub shafts 15 in opposed directions are bevel gear wheels 16, 17, respectively, each enmeshed with a fixed bevel wheel 18 mounted on a flanged bush 19 in the end wall

of the casing, the said bevel wheel 18 being rigidly held to the casing by means of bolts 20.

The rotatable bevel gear wheels 16, 17 are each formed with a boss, the bosses being embraced by eccentric sheaves 21, 22, respectively. The eccentric sheaves are respectively embraced by the heads of connecting rods 23, 24, the distal ends of the connecting rods being connected by pivot pins 25, 26 at opposite sides of an extending boss 13¹ of the traverse cam 13.

The rotatable bevel gear wheels 16, 17 are held on the stub shafts 15 by discs 27 secured to the ends of the stub shafts by bolts 28.

The operation of the traverse mechanism is as follows.

The traverse cam 13 is rotated by the cam shaft 11 and carries the thread guide, not shown, towards one end of the bobbin; the spider 14 also rotates around the shaft 11 causing the rotatable bevel gear wheels 16, 17 enmeshed with the fixed bevel wheel 18 to rotate and, by means of the eccentric sheaves 21, 22 to move the connecting rods 23, 24 to transmit a slight endwise sliding movement to the traverse cam 13 and so to increase the traverse of the thread guide to ensure that the thread is correctly laid on the bobbin adjacent to the flange.

At the opposite end of the throw of the traverse cam 13 an endwise sliding movement is imparted to the traverse cam to ensure that the thread is correctly laid at that end of the bobbin.

The rotation of the bevel gear wheels 16, 17 is timed to synchronise with the traverse of the cam 13 to ensure that the sliding movement of the traverse cam 13 takes place alternately at opposite ends of the stroke of the cam.

The diagram illustrated in Figs. 3 and 4 shows the influence of the eccentrics 21, 22 on the traverse of the cam 13 in achieving the spread of the turn-back coils of thread when winding on to flanged bobbins.

For convenience, it will be assumed that the cam 13 makes seven complete traverses in each cycle, but it is to be understood that the length of the cycle may be varied to requirements by change of the gear ratio.

Referring to Figs. 3 and 4, in which T indicates the thread being wound on a flanged bobbin, the start of the cycle is indicated at S and the end of the cycle at E, the numerals 1 to 7 inclusive each indicating one complete revolution of the cam 13. The arrows in the circles in Fig. 3 indicate the positions of the eccentrics 22, 23 after each half revolution of the traverse cam 13.

The throw of the cam 13 is indicated at X, represented by the distance between the lines A, A, Fig. 4, whilst the distance between the lines B, B, indicates the full traverse length of the mechanism which is the displacement achieved by the combined action of the cam 13 and the eccentric sheaves 21, 22.

It will be seen from the diagram that for all practical purposes, this is the sum of the throw of the cam 13 and twice the throw of the eccentric sheaves 21, 22.

The extent of the spreading zone Z at the end of the traverse length is indicated by the distance between the lines B and C, Fig. 4.

The variations of the lengths of the traverse during the cycle of operations of the traverse mechanism is indicated by the lines T in Fig. 4. Y indicates the length of the bobbin between flanges.

With traverse mechanism as described, it is possible to ensure that thread is correctly laid on the bobbin adjacent to the flange at each end of the bobbin without risk of the thread piling up or alternately causing rounded corners to be formed except in a controlled manner.

I claim:

1. Traversing mechanism for winding machines for winding threads or filaments, having in combination a casing, a shaft journalled in said casing, a toothed driving wheel fast on one projecting end of said shaft, a grooved traverse cam splined on said shaft with freedom for slight sliding movement along the shaft alternately in opposite directions, a spider secured on the cam shaft adjacent to the cam and having oppositely extending arms in the form of stub shafts, bevel gear wheels rotatably mounted on said stub shafts in opposed directions, each enmeshed with a fixed bevel wheel rigidly mounted on a flanged bush in said casing, eccentric sheaves respectively embracing the boss of the adjacent first mentioned rotatable bevel gear wheel and each respectively embraced by the head of a connecting rod the opposite end of which is pivotally connected to the boss of the traverse cam.

2. Traversing mechanism as claimed in claim 1 in which as the traverse cam is rotated by the cam shaft to carry the thread guide towards one end of the bobbin, the spider is also rotated, causing the rotatable bevel gear wheels enmeshed with the fixed bevel wheel to rotate and by means of the eccentric sheaves to move the connecting rods to transmit a slight endwise sliding movement to the traverse cam and so to increase the traverse of the thread guide, a slight endwise sliding movement in the opposite direction being also imparted to the traverse cam at the opposite end of the throw, the rotation of the bevel gear wheels being timed to synchronize with the traverse of the cam to ensure that the sliding movement of the traverse cam takes place alternately at opposite ends of the stroke of the cam, whereby the thread is correctly laid on the bobbin right up to the flange at each end of the bobbin without risk of the thread piling up or alternatively causing rounded corners to be formed except in a controlled manner.

HAROLD WHITTAKER.
